Inventor
Harry L. Grant,
By Samuel Henick,
Attorney

UNITED STATES PATENT OFFICE.

HARRY L. GRANT, OF TAMAQUA, PENNSYLVANIA, ASSIGNOR TO ATLAS POWDER COMPANY, OF WILMINGTON, DELAWARE, A CORPORATION OF DELAWARE.

ELECTRIC BLASTING CAP.

Original application filed July 22, 1925, Serial No. 45,327. Divided and this application filed December 7, 1925. Serial No. 73,637.

To all whom it may concern:

Be it known that HARRY L. GRANT, citizen of the United States, residing at Tamaqua, in the county of Schuylkill and State 5 of Pennsylvania, has invented certain new and useful Improvements in Electric Blasting Caps, of which the following is a specification.

This invention has for its object to provide an electric blasting cap which cannot be prematurely exploded by accidentally, or otherwise, coming in contact with stray electric currents, of any nature, either while being transported or actually used on the job. 10 This application is divisional to my pending application No. 45327, filed July 22, 1925.

Many cases have been recorded where loss of life and destruction of property have been caused by premature explosions of dynamite 20 or other commercial explosives. There was a cause for each of these accidents. Cases are on record where a shot has been prepared for firing and which has prematurely exploded, apparently without cause. It is thus seen that the cause for premature explosions 25 is not always visible to an observer. With the ever increasing use of electrical power and electric labor saving appliances in and about coal mines and quarries and construction projects, there is always the possibility of encountering stray electric currents. These currents may be found flowing through moist earth, between the source 30 of supply and bad joints or bonds of trolley rails or on water or steam pipes. The average electric blasting cap of present American manufacture can be fired by impressing across the ends of its lead wires an E. M. F. of from one to two volts. Potentials of this order cannot be detected without the aid of electrical measuring instruments. Many tests have been made wherein considerably higher potentials have been recorded and yet could not be detected by 40 moist hands of an observer. Not all of the premature explosions have been due to electric blasting caps being exploded by stray currents or accidental contact of same with conductors carrying electric current, but a number of accidents have thus been caused. 45

Among the objects of my invention is to provide an electrically insulated fuse head or igniting device for the electric blasting cap, in order that grounding of the lead

wires or short circuiting of same by touching the side wall of the metal shell, will be prevented. This insulation will make it impossible to complete a circuit through the metal shell and either of the lead wires to which the fuse head is attached. The 55 method of assembly of a safety electric blasting cap, hereinafter described, with the method of application, differs from the character of that shown in U. S. Patent 720,073 issued to Schmidt and Kraunischfeldt and my former U. S. Patent 1,354,100 in that it is not intended to insulate and mechanically support or prevent separation 60 of the lead wires; this now being accomplished by a metal fuse head covered by U. S. Patent 1,407,167 issued to Charles C. Jessen. 70

A further object is to provide a fuse head for an electric blasting cap, insulated from the charge in the base of the shell and 75 from the side wall of the metal shell and which can be used in connection with a safety shunt or some means of short circuiting the exposed ends of the lead wires. When this has been done the electric blasting cap cannot be exploded by the electric current so long as the safety shunt is 80 in place. My new electric blasting cap differs in this respect from other types of electric blasting caps, except the match-head type, and differs from the former match-head type in that the efficiency of the insulation is not dependent upon special forms of assembly in the manufacture of 85 the caps. 90

Further objects and advantages of the invention will be set forth in the detailed description which now follows:

In the accompanying drawing:

Fig. 1 is a side elevation of an assembled electric detonator constructed in accordance with the invention, 95

Fig. 2 is a vertical sectional view through the cap portion thereof, upon an enlarged scale, and 100

Fig. 3 is a detail view, upon an enlarged scale, of a shunt hereinafter described.

Like numerals designate corresponding parts in all of the figures of the drawing.

Referring to the drawing, 5 designates the shell of the detonator. These shells are usually formed of copper or gilding metal, though the invention is not limited to use 105

in conjunction with material of any particular kind.

- Electric detonators now commonly in use utilize igniting elements comprising a ball 5 of match-head material, such as is indicated at 6 and which is ignited when current is permitted to flow through the circuit consisting of lead wires, 7 and 8, and strips, 9 and 10, which may be of tinfoil or other 10 suitable metal, mounted upon a backing 11 of any suitable insulating material such as cardboard or heavy paper. The lead wires, 7 and 8, are insulated through portions of their length, as indicated at 12 and 13, and 15 the outer ends of these lead wires are usually left bare, as indicated at 14 and 15, to adapt them for ready connection to the usual firing cable leading from the blasting machine, (not shown).
- 20 The present invention resides in the employment of a tube 16, of fibre, or other suitable insulating material, in which the ignition assembly is held in centered relation by means of a body of sealing material 17. 25 The lower end of the tube is closed and indented, as indicated at 18, and the match-head projects from the indented end but does not project beyond the line of the lower edge of the tube.
- 30 The charge to be fired by the match-head is indicated at 19, and may comprise a body of mercury fulminate, though any suitable material may be used in this relation. The upper or outer end of the charge 19 is indented and the lower edge of the tube rests directly upon the charge, the space between the charge and the match-head being what is usually known as "fuse head clearance". After the charge 19 has been placed in the 35 shell 5, the ignition assembly, consisting of the electrical elements, the tube 16 and the body of sealing material 17, are inserted in the shell and secured in place by a second body of sealing material of a di-electric 40 and water-proof nature, that is indicated at 45 20. The shell 5 is preferably provided with an annular groove 21, into which the body of sealing material 20 projects, in such way as to resist longitudinal movement of the 50 body of sealing material with respect to the shell 5. It is to be noted that the insulation 12 and 13, extends downwardly from the wires 7 and 8 to a point below the line of the top of the tube 16. In process of assembly, 55 the fuse head passes through a water-proofing operation and is treated with a water-proof and dielectric substance, such as nitro-cellulose varnish, which thoroughly insulates the explosive or flame producing 60 composition, on its lower end, from contact 65 with any form of electrical conductor.

By virtue of the construction described, the electrical circuit element and the fuse head are wholly, electrically, separated from the charge in the base of the shell and from

the metal shell 5. The separation of the fuse head from the charge 19 is made positive by the projection 18 of the tube 16, in conjunction with contact of the lower end of the tube 16 with the indented charge 19, it being understood that this charge is not a loose charge but is of such a nature as to maintain its form and to be held in place by the engagement of tube 16, therewith.

In Fig. 3, I have illustrated a metallic 75 shunt 22, which is disposed directly at the end of the insulation upon the lead wires and which consists of a body of soft metal, pressed into engagement with the lead wires after they have been disposed in crossed relation, and serves to hold the lead wires in contact with each other. Thus, a short circuit is created between the lead wires, so that if the outer ends of said lead wires 80 come in contact with sources of stray electric current, the current cannot pass beyond the shunt constituted by the body 23. Thus, the exposed ends of the lead wires are protected by the shunt at the outer end of the structure and since the electrical elements 85 90 and the match-head at the inner end of the structure are protected by the tube 16 and the coating of dielectric material upon the match-head, it follows that this detonator cannot, under any circumstances, be accidentally exploded by stray electric currents. The shunt 23, of Fig. 3, requires no further description in this application since it has been made the subject matter of a separate 95 application for patent and is not claimed 100 herein.

It is to be understood that the invention is not limited to the precise construction set forth but that it includes within its purview whatever changes fairly come within either 105 the terms or the spirit of the appended claims.

Having described my invention, what I claim is:

1. An electric detonator comprising a 110 shell, a charge of explosive material therein, an electrical fuse head assembly, a tube of insulating material having an open upper end and a closed lower end, in which the fuse head assembly is disposed, a body of 115 sealing material filling said tube and binding the fuse head assembly therein, the lower end of the fuse head projecting through the bottom of the tube and a water-proof sealing material within the shell above said tube, the exposed lower end of the fuse head being coated with a highly dielectric material to electrically insulate it from the charge.

2. An electric detonator comprising a 125 shell, a body of explosive material therein of such consistency as to maintain its form, said body having an indented upper end, a cylindrical tube in said shell and closely conforming to the internal diameter there-

of, the lower edge of which rests upon said charge, said tube having an indented lower end, a fuse head assembly in said tube and comprising a match-head which projects through the indented lower end of the tube, a body of sealing material filling the tube and holding the fuse head in centered relation therein and a body of sealing material within the shell, above said tube and binding the tube in place between itself and the charge.

3. A structure as recited in claim 2, where-

in the fuse head assembly is coated with a highly dielectric material.

4. A structure as recited in claim 2, where-in the shell is provided with an annular internal groove for the reception of the outer sealing material, to prevent longitudinal movement of the same with respect to the shell and to thereby hold the several parts in assembled relation within said shell.

In testimony whereof he affixes his signature.

HARRY L. GRANT.
